UNITED STATES PATENT OFFICE

2,541,866

STOCK CHARGING TRAY

Jaye S. Gamble and Lindsey Stewart, McKeesport, Pa., assignors to National Tube Company, a corporation of New Jersey

Application November 3, 1948, Serial No. 58,085

7 Claims. (Cl. 214—18)

1

This invention relates to stock charging trays for introducing alloying materials to Bessemer converters.

After the charge in a Bessemer converter has been blown and rebarburized, various alloying materials, such as ferromanganese and ferrosilicon, are introduced. In previous practice with which we are familiar, alloying materials are introduced to the charge manually as it is poured from the converter to the teeming ladle. Such practice has disadvantages of being a hazardous operation and of not distributing the alloying materials uniformly throughout the charge.

An object of the present invention is to provide improved stock charging trays which introduce alloying materials mechanically to Bessemer charges while such charges are still in the converter, thereby overcoming disadvantages of previous practices.

A further object of the invention is to provide improved charging trays of sturdy and simple construction and readily maneuverable and which are adapted to contain a plurality of charges of alloying materials for independent introduction to converters.

A further object of the invention is to provide improved stock charging trays which are constructed to introduce materials in the most advantageous place in the converter, namely a little above the slag line at the region of the converter where the pool of metal is deepest and with sufficient force to penetrate the slag layer.

In accomplishing these and other objects of the invention we have provided improved details of structure, a preferred form of which is shown in the accompanying drawing, in which:

Figure 1 is a vertical sectional view of a Bessemer converter and showing in side elevation a stock charging tray embodying features of the present invention positioned for introducing materials to the converter;

Figure 2 is an enlarged top plan view of the tray shown in Figure 1;

Figure 3 is an enlarged side elevational view of the tray;

Figures 4 and 5 are vertical sectional views taken respectively on lines IV—IV and V—V of Figure 3; and

Figure 6 is a vertical sectional view of gate latch mechanism embodied in the tray.

Referring more in detail to the drawing:

In Figure 1 there is shown a Bessemer converter 10 of any standard construction. The converter contains a charge 12 of molten steel which has been blown and rebarburized and

2

which has a slag layer 13. The converter is tilted so that the alloying materials may be introduced from a stock charging tray 14, which embodies features of the present invention.

Tray 14 comprises an elongated body 15, preferably of steel plate and being of uniform rounded cross-section. Said body has an open-ended spout 16 and forward and rear compartments 17 and 18 back of said spout for receiving materials to be introduced to the converter (Figures 2 and 3). Gates 19 and 20 are hinged to the upper edges of the body between said forward compartment and said spout and between said forward and rearward compartments. The preferred mounting for each of said gates includes a transverse shaft 21 pivotally carried by ears 22 upstanding from the walls of the tray body (Figure 5). One end of each shaft carries an enlarged head 23, which is thus rigidly connected with the gate and which has a slot 24 in its outer face extending in a direction perpendicular to the plane of the gate (Figure 6). The tray body has additional upstanding ears 25 and 26 to which latch bars 27 and 28 are pivoted. Said latch bars are cooperable with slots 24 in the enlarged heads to hold the gates closed, but when released from said slots permit the gates to swing open. Preferably a trough-shaped guard 29 protects the latch bars against accidental release and against damage from falling objects. The spout preferably has a cover plate 30. Preferably the back end of the tray carries a counter-weight 31, which is of rectangular cross-section and holds the tray upright when the tray rests on a floor, and which steadies the tray as materials are dumped into a converter.

The mid-portion of the tray has a semi-circular band 32 and laterally extending reinforcing brackets 33, which carry a transverse rod 34 (Figure 4). Brackets 33 also act as stops that limit the position to which the tray is inserted into the mouth of a converter. Chains 35 are connected to the ends of rod 34. A link 36 is pivoted to counter-weight 31, said link preferably being shaped as an isosceles right triangle. A chain 37 is connected to link 36. As shown in Figure 1, chains 35 and 37 suspend the tray above a converter and are adapted to tilt the tray for dumping materials into the converter.

In operation, after the converter charge 12 has been blown, converter 10 is tilted to the position shown in Figure 1. Charges of alloying materials to be introduced to the converter charge are placed in one or both of compartments 17 and 18 of tray 14. The tray is suspended from chains

35 and 37 and spout 16 is inserted within the mouth of the converter to a point where brackets 33, contact the upper inner rim of the converter mouth. Chain 37 is then drawn upwardly until the tray is tilted to the dotted line position in Figure 1, in which it has a slope of approximately 45°. This slope conveniently can be gauged by observing the angle between the top of counter-weight 31 and the contiguous edge of link 36. In the 45° position the top of the counter-weight contacts this edge.

When the tray is fully tilted, the nose of the tray remains clear of the slag layer in the converter, but is in close proximity thereto. The tray is proportioned so that the trajectory of material dumped therefrom delivers this material above the deepest part of the charge. When the tray is thus positioned, latch bar 27, which controls the forward gate, is withdrawn from slot 24. The material in the forward compartment forces gate 19 to open and drops through the spout into the converter. This material drops with sufficient force to penetrate the slag layer and to be well dispersed in the charge. The material in the rear compartment may then be dumped into the same converter by releasing latch bar 28, or the tray may be carried to a different converter to which alloying materials are to be introduced.

From the foregoing description, it is seen that we have provided a stock charging tray which greatly facilitates the introduction of alloying materials to Bessemer charges. The tray is of sturdy and simple construction and conveniently maneuvered for introducing materials to Bessemer converters.

While we have shown and described only a single embodiment of the invention, it is apparent that modifications may arise. Therefore, we do not wish to be limited to the disclosure set forth but only by the scope of the appended claims.

We claim:

1. A stock charging tray for introducing alloying materials to Bessemer converters comprising an elongated body having a spout adapted to be inserted within the mouth of a converter and a compartment back of said spout adapted to contain an alloying charge, a gate hinged at its upper edge to the upper edges of said body between said compartment and said spout and adapted to open by swinging upwardly from its closed position, releasable latch means acting on the hinge of said gate for holding said gate closed, and means attached to said body for suspending the tray above a converter and tilting it to dump material from said compartment through said spout on release of said latch means.

2. A stock charging tray for introducing alloying materials to Bessemer converters comprising an elongated metal body of rounded cross-section having an open-ended spout adapted to be inserted within the mouth of a converter and a compartment back of said spout adapted to contain an alloying charge, a gate hinged at its upper edge to the upper edges of said body between said compartment and said spout and adapted to open by swinging upwardly from its closed position, releasable latch means outside said body and acting on the hinge of said gate for holding said gate closed, a counter-weight rigidly attached to said body back of said compartment and having a flat underface substantially at the same level as the rounded underface of said body, and means attached to the mid-portion of said body and to said counter-weight for suspending

the tray above a converter and tilting it to dump material from said compartment through said spout on release of said latch means.

3. A stock charging tray for introducing alloying materials to Bessemer converters comprising an elongated metal body of rounded cross-section having an open-ended spout adapted to be inserted within the mouth of a converter and a compartment back of said spout adapted to contain an alloying charge, a gate hinged at its upper edge to the upper edges of said body between said compartment and said spout and adapted to open by swinging upwardly from its closed position, a slotted head rigidly connected with said gate externally of said body, a latch bar pivoted to the outside of said body and cooperable with the slot in said head for holding said gate closed, and means attached to said body for suspending the tray above a converter and tilting it to dump material from said compartment through said spout on release of said latch bar from said slotted head.

4. A stock charging tray for introducing alloying materials to Bessemer converters comprising an elongated body having a spout adapted to be inserted within the mouth of a converter and forward and rear compartments back of said spout adapted to contain separate alloying charges, gates hinged at their upper edges to the upper edges of said body between said forward compartment and said spout and between said forward and said rearward compartments and adapted to open by swinging upwardly from their closed positions, individually releasable latch means 35 acting on the hinges of said gates for holding said gates closed, and means attached to said body for suspending the tray above a converter and tilting it to dump material from said compartments through said spout on release of said latch means.

5. A stock charging tray for introducing alloying materials to Bessemer converters comprising an elongated metal body of rounded cross-section having an open-ended spout adapted to be inserted within the mouth of a converter and a compartment back of said spout adapted to contain an alloying charge, a gate hinged to the upper edges of said body between said compartment and said spout, releasable latch means outside 45 said body for holding said gate closed, a counter-weight attached to said body back of said compartment, a link pivoted to the top of said counter-weight and having an edge cooperable with the top of said counter-weight for indicating the 50 angle of tilt of the tray, and means attached to the mid-portion of said body and to said link for suspending the tray above a converter and tilting it to dump material from said compartment through said spout on release of said latch means.

6. A stock charging tray for introducing alloying materials to Bessemer converters comprising an elongated plate metal body of uniform rounded cross-section having an open-ended spout adapted to be inserted within the mouth 65 of a converter and a compartment back of said spout adapted to contain an alloying charge, a gate hinged at its upper edge to the upper edges of said body between said compartment and said spout and adapted to open by swinging upwardly from its closed position, a slotted head rigidly connected with said gate externally of said body, a latch bar pivoted to the outside of said body and cooperable with the slot in said head for holding said gate closed, a counter-weight rigidly 70 attached to said body back of said compartment and cooperable with the top of said counter-weight for holding said gate closed, and means attached to the mid-portion of said body and to said link for suspending the tray above a converter and tilting it to dump material from said compartment through said spout on release of said latch means.

and having a flat underface substantially at the same level as the rounded underface of said body, and means attached to the mid-portion of said body and to said counter-weight for suspending the tray above a converter and tilting it to dump material from said compartment through said spout on release of said latch bar from said slotted head.

7. A stock charging tray for introducing alloying materials to Bessemer converters comprising an elongated metal body of uniform rounded cross-section having an open ended spout adapted to be inserted within the mouth of a converter and a compartment back of said spout adapted to contain an alloying charge, a gate 15 hinged at its upper edge to the upper edges of said body between said compartment and said spout and adapted to open by swinging upwardly from its closed position, releasable latch means outside said body acting on the hinge of said gate 20 for holding said gate closed, a counter-weight rigidly attached to said body back of said compartment and having a flat underface substan-

tially at the same level as the rounded underface of said body, brackets extending laterally from the mid-portion of said body, and means attached to said counter-weight and to said brackets for suspending the tray above a converter and tilting it to dump material from said compartment through said spout on release of said latch means, said brackets being adapted to engage the edge of the converter mouth to limit the position to which the spout can be inserted.
